UNITED STATES PATENT OFFICE.

JOHN A. JUST, OF SYRACUSE, NEW YORK.

PROCESS OF CONDENSING MILK.

No. 888,017.

Specification of Letters Patent.

Patented May 19, 1908.

Application filed November 24, 1906. Serial No. 344,898.

To all whom it may concern:

Be it known that I, JOHN A. JUST, a citizen of the United States, and resident of Syracuse, New York, have invented certain new and useful Improvements in Processes of Condensing Milk, of which the following is a specification, accompanied by drawings.

This invention relates to an improved process of condensing milk and the object of the invention is to obtain a better product than heretofore, and to enable larger quantities of milk to be condensed in a given time than heretofore.

Further objects of the invention will hereinafter appear and to these ends the invention consists of the process for carrying out the above objects substantially as herein-after fully described and claimed in this specification and illustrated by means of the accompanying drawing, which is a longitudinal elevation partly in section of the apparatus preferably employed.

Referring to the drawings, A represents the walls of a chamber, the top B and the bottom C of which are broken away in their length. Since this chamber may be thirty or forty feet square, the size of the chamber in practice is therefore very much larger in actual proportion to the remainder of the apparatus than as illustrated. The bottom C is preferably raised or projected inwardly in the form of a truncated cone having the sides D and top E so that the sides D of the cone and the walls A of the chamber form a chute or collecting space for the dry material.

The chamber which will be designated F is provided with a jacket G for steam or other heating fluid, and is also provided with the suction pipes H communicating with the chamber through the top B. Over the openings of the pipes H are provided fine screens I to aid in preventing the dried material from being carried off by the suction. In front of each screen I are placed revolving blades J adapted to be rotated by motors of any suitable character carried by the brackets K and connected to the blades J. The revolving blades J prevent the dried material, which may be in the form of a powder, from passing off through the suction pipes H.

Within the vacuum chamber F are arranged revolving plates L and O adapted to be revolved at a high speed, which may be from two thousand to eighteen thousand

revolutions per minute. These disks may be of steel and are adjustably mounted on the shaft P by any suitable means, as for instance the set screws Q, whereby the distance between the inner surfaces of the plates 60 may be adjusted as desired. The shaft P extends upwardly to the collar R and the upper portion of the shaft is hollow as partly indicated in dotted lines. A fine aperture S, communicating with the hollow interior of 65 the shaft, is provided between the inner surfaces of the plates L and O to permit the liquid material passing down through the inside of the shaft to pass out between the plates.

The collar or bearing R is carried by the stationary hollow shaft T, suitably supported from the top B of the chamber F and provided with a funnel U. The revolving shaft P is carried in a suitable bearing V in the 70 plate E and is adapted to be driven by any suitable form of motor, as for instance the steam turbine W, provided with the intake X and the exhaust pipe Y, which communicates with the steam jacket G. The jacket 75 is provided with an outlet a, and as shown, extends up around the sides of the vacuum chamber F and around the portion of the inner walls D of the chamber. At the lower portions of the chamber F are provided the outlets b, communicating with the receiving chambers c, which are of sufficient size to receive a substantially large quantity of the material.

Above and below each receiving chamber c 80 are provided the valves d, provided with suitable hand operating devices in the form of cranks e connected to the valve spindles. These valves d may be of any suitable character, preferably one-way valves, and by 85 means of the arrangement of valves shown the material may be withdrawn from the vacuum chamber F without interfering with the normal working conditions of the chamber. When the upper valves d are opened 90 the lower valves d are closed, and before the lower valves are opened, the upper valves should be closed, thereby preventing communication of the chamber F with the outside air. Preferably a hood f is provided 95 over the revolving disks L and O to prevent material from falling upon said disks.

According to the construction described, the liquid to be dried passes out of the aperture or 100 apertures S upon the lower revolving 105

plate L, and is thrown or discharged from said plate into the vacuum chamber F in an "atomized" or finely misted form, permeating substantially the entire chamber F. 5 Substantially as complete a vacuum as possible should be maintained in the chamber F and the heat of the chamber varies in accordance with the nature of the material being operated upon.

10 If liquid milk is being fed to the revolving plate L, the milk is discharged by centrifugal force into the chamber F in atomized form and the evaporating moisture passes off through the suction pipes H, while the solids of the 15 milk are collected in the lower part of the chamber F in the form of an extremely fine dry powder, which is received in the chamber c. When the disks L and O are adjusted very close together, the milk will be discharged at 20 their periphery in a very finely atomized or misted form and will be reduced to a dry powder evaporation of the moisture being complete, but if it is desired to obtain as a product condensed milk the plates L and O 25 should be adjusted further apart and revolved at a lower speed, thereby permitting a larger quantity of milk to flow on to the plate L and issue from between the plates in a rather coarser state of atomization, in which latter 30 case the milk will not be so completely evaporated and will collect in the lower part of the chamber F in a condensed form, which may be withdrawn into the receivers c. As long as the temperature of the chamber F and 35 the speed of the plates and quantity of material fed are all maintained substantially constant, a substantially uniformly evaporated product will be obtained, either as powdered milk or as condensed milk.

40 In the operation of this apparatus, as shown, a stream or prism of milk entering between the disks from the central milk tube is converted into a very thin, disklike film between such disks and is discharged from their 45 periphery in the form of an excessively fine mist, the fineness of this mist depending upon the closeness of approximation of the disks, their speed of rotation, the speed of milk feed, and other similar factors. Though, as 50 shown, discharged at one point near the center of the disks, the milk in radiating centrifugally from this point fills the space between the disks because of the backward lag in traveling from a point of substantially 55 no rotation to the rapidly rotating periphery.

The inner surface of the chamber F may be lined with tin, steel, or iron, which may be readily cleansed and sterilized. The chamber is preferably constructed without 60 corners so that there will be no opportunity for stale products to lodge, and consequently little labor is required to maintain the apparatus in a requisite condition to obtain a product free from extraneous contamination.

In forming a satisfactory dried milk, or even a good grade of condensed milk, wholesome and stable in character and retaining all the milk constituents in an unchanged chemical condition, it has been found that 70 it is very desirable to cause the fatty components to exist in a much finer state of subdivision or emulsification than that in which they exist in the natural full milk, skim milk or cream. When this emulsification is 75 accomplished and the product subjected to desiccation in the apparatus described, a condensed milk or dried product will be obtained, which will keep an indefinite time unchanged in a proper package. On redissolving the 80 product with the requisite quantity of water fresh milk is formed like that from which the product was made without the use of any preserving agent whatever. When milk is sprayed into a more or less heated atmosphere 85 in order to reduce it to dryness, the final result is different in many ways from that obtained in the operation of my process, since its components milk fat and milk serum do not have the same rate of travel through, 90 or friction upon, a spray nozzle and they are therefore discharged in a more or less disaggregated state. One serious fault of the products heretofore obtained by spraying 95 is that the fat quickly becomes rancid and assumes an otherwise disagreeable odor; a fact probably due to the existence of the fat in comparatively large bodies exposed to air.

By atomizing the liquid centrifugally at an extremely high speed as practiced in accordance with my process the dissociation or parting of the various ingredients of the milk is prevented, and those ingredients are brought into most intimate contact and association. Ordinary spraying tends to segregate the ingredients of the milk especially when such sprayed particles are exposed to a heated atmosphere in the process of desiccation. Such a product will not keep and becomes rancid quickly, assuming a cheesy 105 odor, so that for this reason full cream milk has never been successfully desiccated by the spraying process.

By atomizing or misting the milk centrifugally in my apparatus, the product is 110 rendered absolutely uniform and is greatly superior, and is produced at much less cost in a much shorter time than heretofore. Very large quantities of milk can thus be condensed or reduced to a dry powder in a short 115 time. The condensation or reduction of the milk in my process is instantaneous and no time is afforded for harmful changes. Milk ordinarily when condensed in a vacuum pan requires many hours of treatment, this being 120 according to the capacity of the pan, and frequently five or more tons of milk are placed in these pans at one time to be slowly condensed. In my process the milk is supplied in a continuous stream, and the completed 125 130

product is continuously removed, the treatment being practically instantaneous.

The full milk may first be separated in an ordinary separator in order to remove the coarser impurities and dirt generally met with in milk, and by this operation the cream will also be separated. The milk and cream may then be run through a suitable machine to unite and mix the two, the cream being added in proper proportion to the cleansed and separated milk. This mixed milk is then fed into my machine, and is thereby atomized and its constituents brought into intimate contact, infinitely more intimate than existed in the fresh milk. This intimate contact results in the production of a smooth and wholesome article of condensed milk or dry milk powder. If the impurities were not first removed they would concentrate as the milk concentrates and would become more objectionable and pronounced in the finished product, but these impurities are chiefly removed with the dirt or heavy dirt particles. The dirt of milk consists of porous spongy matter, which is teeming with bacteria, and hence my products are especially free from anaerobic and harmful germs.

The condensed milk product may be sweetened or condensed unsweetened as desired. Milk condensed in the ordinary way in a vacuum pan, on standing, or in a store, often cakes more or less and a portion of the product solidifies to a crystalline mass. Milk condensed by my process will not separate its crystalline bodies from the other ingredients. The dry powder obtained by my process is very uniform, owing to the initial uniformity created in the milk before reducing it to the condensed form or dry powder. The fat globules, which in raw milk are seen under the microscope as fairly far apart and of varying sizes, will be seen as small and very close to each other after the treatment to secure additional emulsification. This intimate emulsification or homogenizing once secured will yield a condensed milk or milk powder, which when mixed with a requisite amount of water for restoring the product the liquid milk will hold its fat uniformly throughout, like natural milk and unlike other condensed milk products in which the fat will rise to the surface when the product is mixed with water. The rising of cream is in a way proportional to the size of the butter fat globules and when these are reduced in fineness in the described manner, the rising of the cream is almost indefinitely delayed. This extreme subdivision of the butter fat globules in the misted product issuing at the periphery of the rotating disk renders such product after collection much better adapted for shipment than was the original milk since the cream will not rise to any material extent during the agitation to which the milk must be submitted in transportation and handling,

thereby obviating the annoying non-homogeneity of milk received in cities from distant points. This is also true of the more or less condensed milk collected in the chamber shown, when such chamber is provided with evaporative means; such condensed milk being perfectly uniform as regards its fatty component and displaying no tendency to lose its uniformity during the operations incident to canning and otherwise packaging. In many or most of the customary methods of condensing milk, the butter fat tends to separate out more or less making the production of condensed milk of uniform quality a matter of considerable difficulty.

To recapitulate, my process in its present preferred form comprises purifying the raw milk when necessary by removing solid impurities; reuniting the separated milk and cream when necessary, and in then increasing the fineness of emulsification by accelerating the flow of a stream of milk while spreading it laterally, as by delivering the milk to the center of a rapidly rotating disk in a layer of predetermined thickness, converting this layer into a thin centrifugally radiating and traveling film of increasing thinness until it disintegrates or bursts into a mist-like product of great fineness, containing the butter fat in globules of still greater fineness, each however being still provided with a jacketing pellicle of milk serum, as in the original milk, and collecting this mist-like product as a liquid, with or without more or less evaporation.

I claim and desire to obtain by Letters Patent the following:—

1. The process of treating milk to increase its fineness of emulsification which consists in accelerating the speed of travel of a stream of milk while laterally extending the same until such stream forms a thin layer, converting the layer into a film and continuing the acceleration and lateral extension until the film divides and disintegrates into a fog-like body of homogenized milk.

2. The process of treating milk to increase its fineness of emulsification which consists in centrifugally accelerating the speed of travel of a stream of milk while laterally extending the same until such stream forms a thin layer, converting the layer into a film and continuing the centrifugal acceleration and extension until the film divides and disintegrates into a foglike body of homogenized milk.

3. The process of treating milk to increase its fineness of emulsification which consists in spreading milk out into a thin layer and causing such layer to rotate rapidly and film out laterally until the centrifugal action overcomes surface tension and the circumference of the layer divides and disintegrates into a foglike body of homogenized milk.

4. The process of treating milk to increase

its fineness of emulsification which consists in supplying a stream of milk, spreading such stream out into a thin layer and causing such layer to rotate rapidly and film out laterally 5 until the centrifugal action overcomes surface tension and the circumference of the layer divides and disintegrates into a foglike body of homogenized milk, the flow of such stream being proportioned to the amount of 10 such particles formed so as to preserve the rotating layer.

5. The process of treating milk to increase its fineness of emulsification which consists in delivering the milk continuously upon the 15 surface of a rapidly rotating support and by the action of such support converting the milk into a rotating centrifugally flowing layer, and maintaining the continuity of said layer as such until centrifugal action due to 20 said rotation overcomes the surface tension and cohesion of the milk, causing the circumference of the layer to divide and disintegrate into a foglike body of homogenized milk.

6. The process of treating milk to increase 25 the fineness of emulsification which consists in converting a stream of milk into a thin centrifugally radiating and traveling film, disintegrating and discharging the film circumferentially as a foglike body of homogenized 30 milk and collecting the mist in liquid form.

7. The process of increasing the fineness of emulsification of milk which consists in 35 converting a stream of milk into a thin centrifugally radiating and traveling film and disintegrating and discharging the film as a foglike body of homogenized milk.

8. The process of increasing the fineness of emulsification of milk and condensing the 40 same which consists in converting a stream of milk into a thin centrifugally radiating and traveling film, discharging the film as a mist into a chamber under less than atmos-

pheric pressure and condensing the milk therein.

9. The process of increasing the fineness of emulsification of milk and condensing the same which consists in converting a stream of milk into a thin centrifugally radiating and traveling film, discharging the film as a 50 foglike body of homogenized milk into a heated chamber under less than atmospheric pressure.

10. The process of increasing the fineness of emulsification of milk and condensing the 55 same which consists in converting a stream of milk into a thin centrifugally radiating and traveling film, discharging the film as a foglike body of homogenized milk into a heated chamber under less than atmospheric 60 pressure, speed of travel and speed of feed being so regulated as to permit partial evaporation of water in said chamber, causing such partial evaporation therein and collecting the condensed milk produced.

11. The process of treating and condensing liquids which consists in converting a stream of liquid into a thin, centrifugally radiating and traveling film, discharging the film as a foglike body in a chamber under 70 less than atmospheric pressure and causing evaporation of the liquid therein.

12. The process of treating and condensing liquids which consists in converting a stream of liquid into a thin, centrifugally radiating and traveling film, discharging the film as a foglike body in a heated chamber under less than atmospheric pressure and causing evaporation of the liquid therein.

In testimony whereof I have signed this 80 specification in the presence of two subscribing witnesses.

JOHN A. JUST.
